UNITED STATES PATENT OFFICE.

ELI H. ZEIGLER, OF STEWARTSTOWN, PENNSYLVANIA.

ATTACHMENT FOR BRICK-MACHINES.

No. 875,879.

Specification of Letters Patent.

Patented Jan. 7, 1908.

Application filed September 28, 1907. Serial No. 894,993.

To all whom it may concern:

Be it known that ELI H. ZEIGLER, a citizen of the United States, residing at Stewartstown, in the county of York and State of Pennsylvania, has invented certain new and useful Improvements in the Attachment for Brick-Machines, of which the following is a specification.

This invention relates to that class of brick machines known as soft mud or green brick machines.

In the manufacture of bricks from soft mud, material difficulty is experienced in loosening the brick from the molds so that they may be dumped out onto the receiving pallets. The molds must be more or less violently agitated by knocking or shaking, so as to loosen the green brick, but if this is carried to excess the mud will move toward one or the other side of the mold, so that the bricks lose their rectangular form and must be thrown away.

The only really satisfactory methods so far known to me of accomplishing this result is by the employment of manual labor, the molds being taken from the machine by a workman and violently agitated to loosen the brick. This operation, however, is one requiring considerable skill and the exercise of great strength, inasmuch as each mold contains six or more bricks and is quite heavy, while it is almost impossible for a single workman to keep up with the output of the machine.

Attempts have been made to accomplish the loosening of the brick by shaking or agitating devices, one of these being in the form of a mold carrying table which is agitated through the medium of a stepped cam, but it has been found, by actual test, that the movement imparted by the cam is not sufficiently rapid and abrupt to do the work desired, and these machines have therefore not been adopted.

In other machines, stationary bumpers or knockers have been employed and the mold box reciprocated between them by a workman, while in other cases the mold box has been held stationary and manually operated knockers have been employed. So far as I am aware, however, there is no machine at present in use in which the green brick is successfully loosened from the mold by mechanical means. The main object of the

invention is to enable the work to be done by a man of the necessary intelligence but insufficient physical strength.

A further object of the invention is to provide a device of this type which shall be of simple and economical construction and which may be readily applied to existing brick making machinery.

A further object of the invention is to provide a mold shaking or agitating device in which the mold is loosely mounted on a reciprocatory table that may be operated at any speed, the movement of the mold in each direction being abruptly stopped by a knocker or bumper which, after a number of operations, will effectually loosen the brick without injuring its shape.

With these and other objects in view, the invention comprises the various novel features of construction and combination of parts, which will be hereinafter more fully described and pointed out particularly in the appended claims.

In the accompanying drawings:—Figure 1 is a sectional elevation of a mold agitating device constructed in accordance with the invention. Fig. 2 is a transverse sectional view of the same illustrating also a portion of the mold filling apparatus. Fig. 3 is a plan view, with parts broken away in order to more clearly illustrate the construction. Figs. 4 and 5 are views corresponding to Fig. 1 illustrating modifications of the invention, adapting it to machines of a different type than the one shown.

Corresponding parts in the several figures are indicated throughout by similar characters of reference.

The working parts of the machine are mounted in a suitable frame 10 which may be formed of wood or metal, and which includes in its construction a horizontally disposed table 11 over which the mold boxes 12 pass. The mold boxes are successively moved under a hopper 13 through which the clay or mud is forced for the purpose of filling the mold, and as the molds pass from under the hopper, they are moved in successive order onto a laterally reciprocating table 14.

The table 14 is of a length slightly less than that of the mold box, and is mounted for reciprocatory movement on a plurality of anti-friction rollers 15 that are carried by

pins, or as illustrated in Figs. 4 and 5, where-in the rollers are carried on vertically adjustable brackets.

To the central portion of the bottom of the platform is secured a bar 16 from the ends of which project horizontally disposed tongues 17 that enter ways or guides formed in the frame, these being for the purpose of preventing abnormal movement or jump of the platform while in operation at the end of a stroke. These guides F are formed in the instance shown by chambering the side rails of the frame, and securing cap-blocks 18^a thereon as shown.

From the bottom of the bar 16 extends a yoke 18 having a vertically elongated slot 19 in which fits an anti-friction roller 20 that is carried by a crank pin 21. This crank pin is carried by a disk 22 that is secured to a horizontally disposed shaft 23 journaled in the frame, and the disk is provided with a number of openings 25 spaced at unequal distances, respectively, from the axis of the shaft 23, and arranged to receive a crank pin 21, so that the pin may be adjusted in any one of these openings for the purpose of altering the throw of the crank.

The mold box 12 herein illustrated is of the ordinary type, being provided at its opposite ends with transversely disposed handle bars 26 and said mold is free to slide to a limited extent on the platform 14. The extent of this movement is limited by the transverse strips 27 that are secured to the top of the platform at points slightly beyond the ends of the bottom of the mold box.

Secured to the opposite sides of the frame are knocker arms 28 which preferably are formed of metal and which are disposed in the path of movement of the handle bars 26 or some other rigid part of the mold box.

In the operation of the device, the shaft 23 is rotated at any desired speed to impart seven to eleven reciprocations of the mold for each reciprocation of the plunger within the hopper and this movement is transmitted through the crank pin and its previously described connections to the platform 14. A mold box carried by the platform will be moved between the knocker arms, and the handle bar at one end of the mold box will engage the adjacent knocker arm just before the crank completes its stroke, so that the movement of the mold box will be abruptly stopped while the platform will continue to move for a short distance in the same direction. As the crank pin passes over the center, the direction of movement of the platform will be reversed and the mold box will be moved in the opposite direction, until the other handle bar strikes the other knocker arm, where the operation is repeated. This may be continued for any desired length of time until the green brick is loosened, after which the mold box may be lifted off and

inverted in order to dump the brick onto the receiving pallet.

The attachment herein described was particularly designed for use in connection with the "Henry Martin" machine, but to adapt it for other known machines, I have illustrated in Fig. 4 and 5 to this end.

In the modified construction illustrated in Fig. 4, the crank disk 22^a is located at one side of the machine, and is connected by a pitman rod 30 to an arm 31 that extends laterally from the bar 17 of the platform. In the construction shown in Fig. 5, the crank disk is connected to the bar 17 by means of an angularly bent connecting rod 32. In both of these cases, however, the operation is the same as described in reference to Fig. 1, the crank being used as a means for effecting the reciprocating movement of the platform while the knocker arms serve to abruptly stop the movement of the mold box.

In some instances it will be found expedient to adjust the reciprocating table vertically, and this I provide for by mounting the rollers 15 on stands 15^a projecting from brackets, the latter being slotted vertically, as shown, and secured to the frame of the machine at desired points by manipulation of the securing or clamping bolt, as will be understood.

It will be observed that in all of the constructions described, the operation of the platform proper is not one in which the operating mechanism is subjected to undue jar or strain, inasmuch as the crank will complete its stroke without any stopping or abrupt movement, the operation being as smooth and regular as that of any ordinary crank motion, so that there is no danger of wearing out these parts or danger of accidental breakage, such as is likely to occur in machines where the operating parts are abruptly stopped and started into operation.

To admit of removal and replacement of the platform, or the substitution of another form, I chamber the top side rails of the frame, opposite the rolls 15, and after insertion of a platform and adjuncts I secure the same by the stay blocks.

I claim:

1. In a machine of the class described, a reciprocating platform, a crank through which elongated motion is imparted to said platform, mold box guard strips secured to the platform, and stationary knocker arms disposed in the path of movement of the mold box and arranged to abruptly stop the same without interfering with the movement of the platform.

2. In a machine of the class described, a mold box carrying platform, a supporting means therefor, a vertically slotted yoke depending from the platform, a crank pin arranged to enter said yoke and impart reciprocating movement to the platform, mold box

guard strips arranged near the opposite ends of the platform, and knocker arms arranged to be engaged by said mold box in advance of the completion of the movement of the platform in either direction.

3. In a machine of the class described, a mold box carrying platform, means for imparting thereto a smooth uniform reciprocatory movement, and mold box engaging 10 knocker arms carried by the machine and arranged to abruptly stop the movement of the mold box without interfering with the movement of the platform.

4. In a machine of the class described, a 15 mold box carrying platform, a frame, anti-friction rollers carried by the frame and supporting the platform, a bar secured to the under side of the platform, and having pro-

jecting tongues arranged to enter the guiding slots in the frame, a yoke depending from the 20 bar and provided with a vertically elongated slot, a shaft, a crank disk carried by the shaft and provided with a plurality of openings, a crank pin adjustable into any one of said 25 openings, and an anti-friction roller carried by the crank pin and entering the slots of the yoke, a pair of knocker arms carried by the frame, and mold box guard strips arranged adjacent the opposite ends of the platform.

In testimony whereof I affix my signature 30 in presence of two witnesses.

ELI H. ZEIGLER.
